FERDINAND ROCHOW, OF NEW YORK, N. Y.

Letters Patent No. 95,382, dated September 28, 1869.

IMPROVEMENT IN SAFETY-VALVES FOR STEAM-GENERATORS.

The Schedule referred to in these Letters Patent and making part of the same.

To all whom it may concern:

Be it known that I, FERDINAND ROCHOW, of the city, county, and State of New York, have invented an Improved Safety-Valve for Steam-Generators; and I do hereby declare that the following is a full, clear, and exact description thereof, which will enable those skilled in the art to make and use the same, reference being had to the accompanying drawings, in which—

Figure 1 represents a vertical section through the centre of the valve, and the several parts connected therewith.

Figure 2 represents a plan or top view of a part of the enclosing-chest, showing the manner of attaching the lever R to the outer chest.

Figure 3 represents a vertical section of the valve-box, with the valve and inner cap in elevation, in which is also shown a section of the upper part of a steam-generator and steam dome, to illustrate the application of the safety-valve.

In the accompanying drawings—

A represents the valve-box, which consists of two concentric shells.

The outer one, A, forms the valve-seat, and is fitted solid into a flange, M, which is bolted to the boiler or to the steam-pipe.

The inner one, A¹, forms a hollow cylinder, which is either made to reach directly into the steam-room of the boiler, as shown in the dotted lines A², or which, where this is not practicable, is closed by a disk, B, screwed into or bolted to it, and connected by a small separate pipe, O, with the interior of the steam-room of the boiler.

Both these shells are connected together by a sufficient number of ribs C C.

The outer cylinder A extends above the inner one, and is so much greater in diameter than the inner one, as to leave an open passage, O, between them, as large as the area of the opening in the valve-seat, and through this passage the steam escapes, as indicated by the arrows, when the valve lifts off its seat.

The valve is formed cylindrical at its lower part D¹, where it is turned off and furnished with a sleeve, E, which is bolted tightly to it from underneath, through an annular horizontal flange, by bolts a. This sleeve is fitted so as to work easily in the cylindrical part A¹ of the valve-box, so that this part of the valve acts like a piston within the inner cylinder A¹.

The connecting-neck D of the valve is of diminished diameter, and made semi-spherical, so as to present the least possible resistance to the flow of the escaping steam; and is also furnished with three or four wings b b, by which the valve is guided in its seat and case.

The valve D is kept on its seat by the pressure of the spring G acting on the washer H, nuts J J, and stem K.

The spring is held in its place by a cap, L, the latter being screwed solid on to the valve-box A by an annular ring, L², and this cap covers the spring in its whole length, and protects it against injury from the outside.

The annular ring L² is connected to the cap L by two legs f, so as to leave sufficiently large openings in the cap, near the valve-seat, to allow the steam to escape freely beneath the cap L.

The stem K is guided at its upper end by the downward-projecting boss l, cast within the cap L, being bored out sufficiently deep to allow the stem K to rise the desired height therein.

The washer H fits loosely on the stem K, and a feather, c, fastened into the washer, works in a corresponding groove in the stem, so that the stem cannot turn in the washer, while the lower end of said stem passes into a central opening in the valve, and is fitted into a socket in the closed bottom of said valve.

The operation of this valve is as follows:

As long as the valve closes tight on its seat, the steam from the boiler will exert on it the following pressures:

First, in the upper part of the cylinder A¹, (which cylinder is of greater diameter than the opening in the valve-seat,) a downward pressure, due to the difference between the area of cylinder A¹ and of the opening in the valve-seat.

Second, in the lower part of the cylinder A¹, an upward pressure, due to the full area of the cylinder A¹.

The difference of both, which is simply a pressure due to the area of the opening in the valve-seat, is, therefore, the total pressure on the valve, as long as it is on its seat. When the valve just commences to raise, the pressure of the spring, and of the steam on the valve, are just on an equilibrium. Practically, the spring is adjusted to exert the proper pressure on the valve, by screwing up the nuts J J so much that the valve will just commence lifting when the pressure in the boiler, which is indicated by a steam-gauge, has reached its intended limit.

When the valve commences to lift off its seat, and steam to blow off, the steam-pressure in the upper part of cylinder A¹ will gradually diminish as the steam escapes more rapidly. There will also be a greater pressure against the arch d², in the upward direction, against which the escaping steam strikes, than against the lower part d¹ of the semi-elliptical neck. This surplus of pressure in an upward direction increases with the rapidity of the motion of the steam, proportionately to the distance which the valve is lifted off its seat. If the cylinder A¹ were of the same diameter as the opening in the valve-seat, this surplus of pressure in the upper part of the cylinder A¹ would be the total increase of pressure of steam against the valve, in an upward direction from the point when the valve

commenced to rise, as the pressure in the lower part of the cylinder A^1 is from that point constantly the same, whatever distance the valve may lift off its seat, viz, the pressure inside of the steam-boiler, it not being affected by the flow of the escaping steam.

The above-described increasing surplus of pressure in lifting the valve, has therefore to overcome the increased tension of the spring. But this surplus of pressure can be increased by giving the cylinder A^1 the proper diameter, because the additional annular area thus added to the cylinder A^1 and piston D^1 by means of the sleeve E , is always acted upon with the full boiler-pressure from below, while the pressure on top of it is decreasing with the rapidity of the escaping steam, or with the distance which the valve rises from its seat.

When the valve has been raised so high that the escaping steam has reached its maximum speed (which ought to be the height of lift of a perfect safety-valve) in the upper part of the inner cylinder A^1 , then the action of the steam in this part would remain unaltered on the valve, whether it raised more or not, and if there were any surplus of upward pressure left, the valve would not commence to come down on its seat again before there had blown off so much pressure in the boiler, that this surplus of pressure were reduced to nothing.

Thus, by giving the diameters of the inner cylinder A^1 , and the opening in the valve-seat of the outer cylinder A , the proper proportion, the valve may, first, be enabled to raise the required height, even against the increasing tension of a spring, relieving the boiler of an undue pressure in the shortest possible time; and, second, it may be enabled to keep open until the pressure of the boiler has fallen any desired amount below the pressure at which it commenced to raise.

A cylindrical lock-up chest, P , is screwed on to the right-angled flange M , in such manner that an inner rim, p , bears hard on to the valve-box A , and securely holds it in its place. This lock-up case covers the whole mechanism, and is furnished with a nozzle, Q , for the escape of the steam, opposite to which there is a partition, d , in the interior, cast across the opening, so that no meddling with the valve is possible through this nozzle.

There is, further, an opening in the lock-up case left between two eyes $e e$, cast on the outside of the chest P , and the latter is fitted with a screw-thread, so that when it is screwed down hard upon the flange M , this opening is opposite one of the connecting-legs f on the cap L .

A forked lever, R , by which the valve may be raised from outside, in order to blow off steam, reaches through this opening into the chest, under the washer H , on each side of the nuts $J J$, the connecting-leg f being made narrow enough to allow the fork of the lever R to embrace it.

A bolt, S , passing through the eyes $e e$ and the lever R , makes its fulcrum, and connects it to the chest P , while a lip, h , is cast on the inside of the chest, under this lever, to support it and prevent its moving downward and bearing on the valve.

The cap L is screwed on to the valve-box A with a left-hand thread, V , and the chest P on to the flange M with right-hand or reverse thread W , so that when the lever R is secured in its place, it is impossible to unscrew the chest P , as an effort to do so would cause the lever fitting over the leg f to screw the cap L harder on to the valve-box A , and thus the outer case and the inner cap are completely locked together.

An eye-splint, i , is put through the end of the bolt S , which extends outside of the eye e , and a lock put into the eye of this splint, so as to prevent the bolt from being withdrawn.

The application of the safety-valve to a boiler is represented in fig. 3 of the drawings, and it will be

seen that a steam-pipe extends from the valve-box into the steam-dome.

To this steam-pipe, I prefer to attach an umbrella-like shield or disk, somewhat below the opening in the dome, for the escape of the steam, so as to break or interrupt any current of water which may be drawn up by the force of the escaping steam, when this should blow off too suddenly, and cause the water to fall back again into the boiler. The arrows in this figure show the direction of the escaping steam when the valve lifts.

The sleeve E is necessary whenever the cylinder A^1 is larger than the opening in the valve-seat, because, if the piston-part D^1 of the valve were simply made larger, the valve could not be got in, as it has to be put in from the top, through the opening in the seat, and the sleeve E afterward screwed to it from below. By making the sleeve E larger or smaller, any surplus of pressure can be obtained, as above described.

I have found that a valve may be set to blow off, say at fifty pounds pressure, and that this pressure can be increased to one hundred pounds before the valve will open as wide as it ought, the pressure under the valve being only fifty pounds when it is raised so much off its seat. I can proportion my valve so as to raise enough to give the whole area of the openings through all the passages, maintaining no higher pressure than as much as when it is started to blow off.

This safety-valve may also be weighted by a lever and weight, as represented in fig. 4. In this case the sleeve E is not necessary, as the weight does not increase with the height the lever lifts. The cylinder A^1 need not, in this case, be made larger than the opening in the valve-seat, the sleeve E , by which the increased diameter of the valve is effected, being only a necessity in combination with a spring-weighted valve. When the valve, therefore, is weighted by a spring, the removable sleeve is necessary, to increase the diameter of the valve.

Figure 4 shows the application of my invention to a safety-valve weighted by a lever, the valve-box A being arranged exactly as in fig. 1, with the piston-part D^1 of valve D rather smaller than the opening in the valve-seat, at least, not larger, so that there is no sleeve E required to put in from below.

The lever U is hung in a hinge, T , cast on the box A , and it has sufficient upward movement to allow the valve to raise its intended height, as seen at the dotted lines $n n$.

Figure 5 is a modification of fig. 1. Although the piston-part D^1 of valve D is larger than the opening in the valve-seat, the disk B is done away with by the arrangement of the separate opening A^2 , which forms the valve-seat proper, and which is secured on box A by the cap L , when screwed down hard. In this, the valve D^2 and piston-part D^1 have to be made in two separate pieces, and the annular valve is screwed to the neck D after the seat A^2 is placed over the valve, as shown in dotted lines; or the piston-part D^1 has to be made small enough to slip through the valve-seat, and a sleeve secured to it afterward, analogous to sleeve E . By this modification, the valve may be readily withdrawn by simply unscrewing the cap L .

Having described my invention,

I claim—

1. A valve-box of a safety-valve, having an interior cylinder, A^1 , which is, at its upper end, in direct and unobstructed communication with the opening in the valve-seat D^2 , and, at its lower end, in permanent free communication with the interior of the boiler only, while the escape-opening, with which its upper end communicates, is also in free and unobstructed communication with the interior of the boiler, when the valve is made to form a piston, closed at its lower end, constructed and arranged substantially as before described.

2. The combination of the annular sleeve E with the cylindrical portion D¹ of the valve, and the inner cylinder A¹ of the valve-box, substantially as before described.

3. The inner cap L, constructed with a left-hand screw-thread, V, and the enclosing-chest P with a right-hand screw-thread, W, in combination with the forked lever R, whereby the said cap and chest are securely locked together, substantially as before described.

4. The inner enclosing- cap L, constructed with legs f f, and an annular screw-ring, L², in combination with the lever R, constructed so as to embrace one of the said legs, thus constituting the lock, substantially as before described.

5. The inner cap L, for enclosing the spring G, and the outer chest P, for enclosing said cap, constructed and arranged substantially as before described.

6. The inner cap L, for enclosing the spring G, constructed with a cylindrical hollow guide, l, projecting within the spring, so as to form a guide for the spindle K, substantially as before described.

7. The guard d, arranged above the bottom of the cap L, and with reference to the exterior of said cap, and the escape-pipe Q, so that, in connection with the cap, a double protection is afforded to the adjusting-devices of the spring, substantially as before described.

8. The construction and arrangement of the chest P, forked lever R, bolt S, eye-splint i, and flange M, with the cap L, valve-box A, and valve D, constructed and arranged substantially as before described.

FERDINAND ROCHOW.
